HAIR CLASP

Moses F. Boxer, San Francisco, Calif.

Application March 22, 1956, Serial No. 573,223

7 Claims. (Cl. 132—46)

This invention relates generally to hair clasps.

Conventional hair clasps have been found to be objectionable in that they do not grasp the hair tightly enough and because they are generally so large and bulky that they cannot be concealed under the hair. These clasps have been difficult to adapt to the various types of hearing aid devices, particularly when it is desired to use the same type of device for supporting any one of the components of the hearing aid such as the receiver, transmitter or the cord. Such clasps also are not adapted for fastening men's toupees, where adhesives cannot be used or for fastening women's glamour hair adaptations such as falls, curls and pony tails.

In general, it is an object of the present invention to provide a hair clasp which can be readily fastened in the hair and can be used for carrying or fastening other objects in the hair.

Another object of the invention is to provide a clasp of the above character which will grasp the hair firmly without cutting the hair.

Another object of the invention is to provide a clasp of the above character which is suitable for supporting one or more of the components of a hearing aid.

Another object of the invention is to provide a clasp of the above character which can be used for supporting objects of various sizes.

Another object of the invention is to provide a device of the above character which can be used for fastening men's toupees and women's glamour hair adaptations.

Additional objects and features of the invention will appear from the following description in which the preferred embodiment has been set forth in detail in conjunction with the accompanying drawing.

Referring to the drawing:

Figure 1 is a bottom plan view illustrating a hair clasp incorporating the present invention and showing a hearing aid receiver cord supported thereby.

Figure 2 is a side elevational view of the hair clasp shown in Figure 1.

Figure 3 is a top plan view of the clasp shown in Figure 1 without the hearing aid receiver cord.

Figure 4 is a side elevational view similar to the view of Figure 2 but showing the clasp in an open position and supporting a hearing aid receiver rather than a hearing aid cord.

Figure 5 is an enlarged cross-sectional view taken along the line 5—5 of Figure 1.

Figure 6 is an enlarged view taken along the line 6—6 of Figure 2.

This invention, as illustrated in the drawing, consists of a pair of leaves 11 and 12 which are formed of a suitable spring metal. Suitable means is provided for forming a hinged connection between leaves 11 and 12 and

2

consists of a pair of knuckles 13 on leaf 12 and a knuckle 14 on leaf 11 which are adapted to interfit to form a barrel for the reception of a pin 16. Other conventional means such as a ball and socket connection may also be used for forming a hinged connection between the leaves.

Leaf 11 has been formed to provide a hook 17 and leaf 12 has been formed with a raised point 19 which is adapted to engage a V-shaped notch 21 in hook 17 to fasten leaf 12 to leaf 11. It is desirable to form member 10 12 slightly curved as shown particularly in Figure 4 so that the convex side face of leaf 12 is facing the leaf 11, is caused to tightly engage leaf 11 when the raised point 19 is in engagement with the notch 21.

A pair of ears 23 are provided on each side of leaf 11. The ears 23 are provided with holes 24 for a purpose hereinafter described. Notches 26 are provided in the leaf 11 adjacent the ears 23 and are also provided for a purpose hereinafter described. A groove 27 is provided in leaf 11 adjacent the pair of ears on each side 20 of the leaf and extends substantially parallel to the longitudinal axis of the leaf. The leaf 11 is also provided with a raised portion 28 which extends for a substantial distance along the longitudinal axis of the leaf.

Leaf 12 is provided with a cut out portion 31 which 25 is adapted to overlie the raised portion 28 of leaf 11. The width of the cut out portion gradually increases from the rear to the front and permits sideways movement of leaf 12 relative to raised portion 28. Leaf 12 is also provided with widened portions 32 which are adapted to 30 overlie grooves 27 but serve to prevent entry of the leaf 12 into grooves 27.

Operation of the clasp may now be described as follows: To close the clasp from the position shown in Figure 4, it is merely necessary to spring the leaf 12 into 35 engagement with leaf 11 in such a manner that the V-shaped groove generally overlies raised portion 28. Leaf 12 is then shifted laterally in one direction or the other until the raised point 19 engages the hook 17. The widened portions 32 prevent the leaf 12 from entering the 40 grooves 27. If the leaf 12 were permitted to enter the grooves 27, it would be difficult to shift the leaf 12 laterally with respect to leaf 11 and thus would make it difficult to remove the raised point from under the hook 13. In opening the clasp, it is apparent that it is merely 45 necessary to depress the raised point 19 slightly and then move the same laterally in either direction until it is freed from the hook 17.

The hair clasp is particularly suitable for carrying devices in the hair. In Figures 1, 2 and 5, I have shown the 50 hair clasp used for supporting a flexible electrical cord 34 which may form a part of an electrical hearing aid such as the cord which interconnects the transmitter and receiver of a hearing aid. The cord 34 is positioned on the bottom of leaf 11 along the longitudinal axis of leaf 11 and underlying the raised portion 28 so that it will fall into the groove provided on the underside of leaf 11 by the raised portion. The cord 34 is retained thereon by a resilient rubber band 36 having portions 36a, 36b, 55 36c and 36d. It will be noted that portions 36a and 36b engage the cord 34 and underlie leaf 11 and that portions 36c and 36d lie in grooves 27.

When a plait of hair is positioned between leaves 11 and 12, the hair is engaged by portions 36c and 36d of the rubber band to provide additional friction for retaining the clasp in the desired position on the plait of hair. 60 It will be evident that the rubber band 36 must be of such a size that it will be stretched somewhat when it is

applied over cord 34 and leaf 11 so that the cord 34 will be firmly grasped by the rubber band.

When the hair clasp is utilized for supporting a hearing aid receiver cord, the clasp is generally inserted in the hair on the back of the neck so that the clasp will be completely hidden and so that the cord will extend down the neck of the user to the transmitter which is normally carried in a shirt pocket of a similar convenient place. The receiver is normally connected to the ear by any suitable means such as an ear mold. When the hair clasp is applied in this manner, the lock or plait of hair will be firmly grasped by the hair clasp; however, if the wearer should apply an abnormal pull to the cord, the cord will slip relative to the clasp because of the yieldable tension provided by the rubber band.

In Figure 4, the hair clasp has been shown connected to a receiving unit 37 that is provided with an air tube 38. The receiving unit is connected to the clasp in a manner similar to the attachment of the cord. A rubber band is looped about the receiving unit 37 in such a manner that one portion of the rubber band engages one end of the receiving unit and another portion of the rubber band engages the other end of the receiving unit. The clasp may then be inserted in the hair in a manner similar to that hereinbefore described.

If desired, in supporting a receiving unit in the hair, instead of fastening the clasp directly to the receiving unit, a pair of clasps can be used. For example, one clasp can be fastened to the cord 34, and another clasp can be fastened to the air tube 38. Both clasps can then be inserted in the hair to support the receiving unit. If the wearer wishes to overcome the discomfort of a cord running down the back of the neck, the transmitting unit of the hearing aid may be secured to the clasp by the use of screws connecting the ears 23 to the transmitting unit.

When the clasp is being used by a person wearing a wig or toupee, the holes in the ears 23 may be utilized for sewing the clasp into the wig or toupee.

The clasp may also be used for fastening men's toupees where adhesive cannot be used. It can also be used for fastening women's glamour hair adaptations such as falls, curls and pony tails. The clasp is sewn or fastened to the object to be supported.

It will be evident that various changes can be made within the scope of the appended claims. For example, in place of metal, part or all of the device can be made of a suitable plastic color to resemble skin or hair to facilitate hiding in the hair. The grooves 27 can be eliminated if rubber bands are not used. Also the rubber band 36 can be of any suitable elastic material, such as synthetic rubber.

It will be apparent from the foregoing that I have provided a new and improved hair clasp which can be readily concealed in the hair and utilized for supporting objects such as components of hearing aids within the hair. It is also apparent that the clasp can be utilized for securing hats to the hair, such as those worn by nurses or for fastening men's toupees or women's hair adaptations.

I claim:

1. In a clasp adapted to engage a lock of hair and support an object, a leaf, an additional leaf hinged to said first named leaf, said additional leaf being curved to provide a convex surface adapted to be sprung into engagement with said first named leaf to engage a lock of hair, a hook with a notch therein formed on the free end of said first named leaf, a raised portion formed on the free end of said additional leaf and adapted to engage the notch in said hook when said additional leaf is sprung into engagement with said first named leaf, a plurality of slots in said first named leaf, and resilient rubber-like means for engaging said slots and adapted to yieldably attach an object to said first named leaf.

2. In a clasp adapted to engage a lock of hair and support an object, a leaf, an additional leaf hinged to said first named leaf, said additional leaf being curved to pro-

vide a convex surface adapted to be sprung into engagement with said first named leaf to clasp a lock of hair, a hook with a notch therein formed on the free end of said first named leaf, a raised portion formed on the free end of said additional leaf and adapted to engage the notch in said hook, one of said leaves being formed with a raised portion extending longitudinally of the leaf, and the other of said leaves being formed with an elongate opening or cut out extending longitudinally of the leaf and overlying said last named raised portion when said first named raised portion is in engagement with said hook.

3. In a clasp adapted to engage a lock of hair and support an object, a leaf, said leaf being formed with a groove on each side edge of the leaf, said grooves extending substantially parallel to the longitudinal axis of said leaf, an additional leaf hinged to said first named leaf, said additional leaf being curved to provide a convex surface adapted to be sprung into engagement with first named leaf to engage a lock of hair therebetween, a hook formed on the end of said first named leaf, a raised portion formed on the free end of said additional leaf and adapted to engage said hook when said additional leaf is sprung into engagement with said first named leaf, a plurality of slots in said first named leaf, and resilient rubber-like means engaging said slots and adapted to yieldably attach an object to said first named leaf, said grooves in said first named leaf being adapted to receive portions of the rubber-like means.

4. A hair clasp as in claim 3 wherein an elongate raised portion is formed on said first named leaf and wherein said additional leaf is formed with an elongated cut out adapted to accommodate said raised portion when said leaves are brought into engagement with each other.

5. A hair clasp as in claim 4 wherein said rubber-like means has spaced portions of the same embracing said object and other portions of the same extending longitudinally of the first named leaf on the side of the leaf opposite the side to which the object is secured.

6. In a clasp adapted to engage a lock of hair and support an object, a leaf, an additional leaf hinged to said first named leaf, said additional leaf being curved to provide a convex surface adapted to be sprung into engagement with said first named leaf to engage a lock of hair, a hook formed on the free end of said first named leaf, a raised portion formed on the free end of said additional leaf and adapted to engage said hook when said additional leaf is sprung into engagement with said first named leaf, a plurality of slots in said first named leaf, and resilient rubber-like means for engaging said slots and adapted to yieldably attach an object to said first named leaf.

7. In a clasp adapted to engage a lock of hair and support an object, a leaf, said leaf being formed with a pair of grooves extending substantially parallel to the longitudinal axis of the leaf and being spaced on opposite side edges of the same, a pair of ears formed on each side edge of said leaf, said leaf also being formed to provide slots adjacent said ears, an additional leaf hinged to said first named leaf, said additional leaf being curved to provide a convex surface adapted to be sprung into engagement with said first named leaf to clasp a lock of hair, a hook formed on the free end of said first named leaf, a raised portion formed on the free end of said additional leaf and adapted to engage said hook, one of said leaves being formed with a raised portion extending longitudinally of the leaf, and the other said leaves being formed with an elongate opening or cut out extending longitudinally of the leaf and overlying said last named raised portion when said first named raised portion is in engagement with said hook, and rubber-like means engaging said slots and adapted to yieldably attach an object to the first named leaf, said grooves in said first named leaf receiving portions of the rubber means, spaced portions of the rubber means em-
